ROBERT W. BURROWS, OF PETALUMA, CALIFORNIA; MABEL BURROWS, EXECUTRIX OF SAID ROBERT W. BURROWS, DECEASED, ASSIGNOR TO WILLIAM K. JAQUITH, OF PETALUMA, CALIFORNIA

PACKING PAD

Application filed August 13, 1930. Serial No. 475,020.

The invention relates to a pad or buffer which is adaptable to use in cushioning the inner faces of a box container for packing fruit, or which may be formed cylindrically or conically for other forms of packing, such as around electric light bulbs, or beverage bottles, or any other similar uses where a padding or cushioning member is desired. Many expedients and forms of padding devices for such uses have been tried with varying degrees of success, but it has been found that most of these padding members or materials have faults or short-comings which offset their usefulness, and many types are so expensively constructed as to be prohibitive in commercial use.

Among the problems to be met in such a pad are to provide lightness of weight and compactness in bulk for shipment, and for shipment it is desirable to have the pad of material compressible in bundles and which will resume its cushioning qualities when released from the compressed bundles.

It also is desirable to have flexibility to the pad so that it may be shaped around irregular surfaces and in corners; also that it may be tough enough to be bent without breaking and crushed without destroying its cushioning effect; also that it be of relatively soft material so that the pad itself will not injure delicate products packed therein, such as is often done when packing fruits with the ordinary corrugated packing board which is made of relatively rigid substance.

In order that the advantages of this invention may be readily distinguished from the known art, it is advisable that the terms craped or crimped paper be distinguished from the term corrugated board. As used herein, corrugated board is referred to as the commercial product having parallel ridges and having a comparatively stiff body, and capable of supporting its own weight without substantial sagging lengthwise of the corrugations, when cut into pieces approximately six inches longitudinally parallel to the corrugations by one inch transversely of the corrugations and supported firmly at one end so as to have about five inches free and

subject to its own weight horizontally. The term craped or crimped paper is referred to as a sheet body having crinkles therein and of such nature that it may be termed flaccid, or which will sag of its own weight when supported in the manner described above.

It is the object of this invention to provide a tough flexible pad having absorbent qualities, having a spongy resiliency, which may be used flat, or folded around an object, which may be bent without breaking, and compressed without losing its resiliency; also to provide a pad wherein the thickness may be readily and easily adjusted, and to improve generally upon cushioning packing pads.

With the above mentioned and other objects in view, the invention consists in the novel construction and combination of parts hereinafter described, illustrated in the accompanying drawing and pointed out in the claims hereto appended; it being understood that various changes in the form, proportion, size and minor details of construction within the scope of the claims may be resorted to without departing from the spirit or sacrificing any of the advantages of the invention.

To more clearly comprehend the invention, reference is directed to the accompanying drawing, wherein:

Fig. 1 is a perspective of pad.

Fig. 2 is a lateral transverse section on line 2—2 of Fig. 1.

Fig. 3 is a vertical elevation of pad adapted to cylindrical form, showing overlapping ends.

Fig. 4 is a vertical elevation of pad adapted to conical object, showing how the pad may be crushed to fit the object.

Fig. 5 is a transverse section of a single sheet of the material of which pad is made.

Fig. 6 is perspective of modified form of pad.

Fig. 7 is a perspective of modified form of pad.

Fig. 8 is a modification in perspective, showing the superposed layers in regular uniform formation, but so arranged that the crimping of abutting layers is angularly positioned relatively.

Referring to the drawing, in which like characters of reference designate similar parts in the several figures, 5 represents a pad generally which is composed of a plurality of 5 superposed layers of crimped paper 6. This paper is a well known commercially manufactured tough fibrous product and has crimpings formed therein, so that the surface thereof is provided with a large number of 10 irregularly placed and irregularly sized projections or indentations 7 from the general plane of the paper, as shown in Fig. 5 and Fig. 6. These projections or indentations may be formed on either or both sides of the 15 general plane of the paper, but I prefer that they be on one side of said plane only since that is a commodity readily obtained in the market.

This crimping will increase the cross sectional thickness of the paper, depending on 20 the coarseness of the crimping, and I prefer to use crimping of such coarseness so that the extreme planes of the crinkled sheet increase the normal thickness of the paper about four-fold. These crimpings in the paper are 25 formed with irregular spacing and are irregular in size, and therefore when superposing the layers, the projections of indentations, as the case may be, do not nest, and in 30 that manner they form a pad about four times the normal thickness of the paper, with the crimped portions forming a cushion body which is soft and flexible.

Since these projections or indentations do 35 not nest, they may be formed in the superposed layers of paper in a uniform direction, or the crimping may extend in opposite directions in the abutting superposed layers, and when extending in opposite directions, the 40 projections or indentations may be made uniform, if desired, so long as the paper bearing them is flexible in all directions, as shown in Fig. 8.

In some uses of the pad, it is preferred that 45 these superposed layers of crimped paper be bound by an envelope 8 having a smooth outer surface, which will maintain the positioning of the sheets and facilitate handling.

This envelope is particularly desirable in 50 the pads when used for packing fruit, especially fruit which is easily bruised and injured, such as grapes, ripened peaches, ripe figs, and the like, since it provides a smooth sliding surface to prevent chafing of the skin 55 of the fruit, due to rough handling in packing or vibration in transportation. The envelope extends parallel with one face of the pad and around its ends and is attached to the reverse face by flaps or wings 9 which may be glued 60 to the reverse side of the pad.

For use in packing bottles, electric light bulbs and the like, the pad may be constructed cylindrically, as shown in Fig. 3 and Fig. 4, and when used for padding articles of this 65 nature, it is not essential that a smooth-faced

envelope be used, in which event the upper and lower sheets of the crimped paper may be extended beyond the ends 10 of the interposed sheets, as in Fig. 6, and the extending ends lapped over and glued when the pad 70 is formed into a cylindrical structure, as shown in Fig. 3. The body of the pad having great flexibility by reason of its body material, may be formed to fit irregular objects, such as bottles, so that they may be packed 75 to greatest advantage to save space, (see Fig. 4).

The superposed layers of crimped paper afford other advantages over any other form 80 of pad, and especially over the usual corrugated board, excelsior, straw, stripped or shredded paper and the like. Corrugated board being relatively stiff will injure delicate products; if the corrugations are crushed they have no resiliency to spring back to normal shape; if bent transversely of the corrugations, the board cracks; in packing the boards for shipment they cannot be compressed under pressure to less than their normal size. Excelsior and shredded paper and 85 straw are hard to handle in loose form and create litter and refuse, they are highly inflammable, and require a much heavier cover or envelope, and, if packed under pressure for shipment, they do not resume their initial resiliency unless the shreds are manually or mechanically loosened. Crimped paper, on the other hand, is absorbent of moisture, flexible in any direction, resilient, soft, and adapts itself most readily to the making of 90 cushioning pads of varying thicknesses, dependent on the use to which it is to be put, by merely eliminating the number of superposed layers, and thus diminishing the thickness and the cushioning effect of the pad, and 95 its bulk and cost.

If desired, the facing sheet 8 of the pad which is intended to abut fruit or other moist objects may be waterproofed with paraffine or other suitable waterproofing compound. 100

While the word crimped is used in the claims, it is contemplated that I claim other forms of laterally projecting portions from sheets of flaccid material as distinguished from relatively stiff material, the flexibility 115 of which is substantially opposed by crimping, corrugations, waving or the like.

I claim:—

1. A packing pad comprising superposed layers of flaccid sheets of crimped paper and a facing sheet having a waterproofed surface, and provided with end wings adapted for folding over the ends of the superposed crimped layers and for attachment to the reverse side of the pad from the facing sheet. 120

2. A packing pad comprising superposed layers of flaccid sheets of crimped paper forming an inner body of the pad, and a flexible outside binder sheet of greater length than the inner body sheets, said outside binder 125

sheet being provided with wing portions adapted to be fixedly attached to the pad so as to position the inner body sheets in pad-forming relation.

- 5 3. A packing pad comprising a face sheet and a back sheet having their respective corresponding ends connected at opposite edges so as to form an envelope open at the remaining edges, and a crimped flaccid sheet interposed between the front and back sheet, said facing sheet having a surface resistant to absorption of moisture.
- 10 4. A packing pad comprising a rectangular envelope open at two sides and having a face

15 sheet of flaccid material, and a back sheet secured thereto at opposite ends, and a plurality of sheets loosely interposed between and parallel to the face sheet and back sheet and said interposed sheets having portions of their respective bodies upformed from the normal plane of the sheet.

- 20 5. A packing pad comprising a pair of outer sheets and a plurality of overlying parallel inner sheets of flexible crimped fibrous material, one of said outer sheets being of greater width than the inner crimped sheets, thereby providing a flap adapted for folding over an end of the inner sheets, and the ex-

treme edges of the inner sheets being free of connection to the outer sheets.

6. A packing pad comprising a plurality of overlying flaccid sheets including a face sheet and a back sheet and a crimped flaccid sheet interposed between said face sheet and back sheet, a portion of the periphery of the pad being defined by extreme free edges of the sheets, said face sheet and back sheet having fixed relative connection at radially outward portions and having other radially outward portions at which the extreme edges of the face sheet and back sheet are free from relative connection.

7. A packing pad comprising a plurality of parallel sheets and including a face sheet and a back sheet fixedly held relative to each other at two end portions, and a crimped flaccid sheet of tough fibrous material interposed between the face sheet and back sheet, said facing sheet having a surface of greater degree of smoothness than the crimped interposed sheet, and said pad having other end portions at which the extreme edges of the individual sheets are free from relative connection.

ROBERT W. BURROWS.
